UNITED STATES PATENT OFFICE.

CHARLES H. PFEIL, OF CHICAGO, ILLINOIS.

DESIGN FOR A RING.

No. 38,111.

Specification for Design.

Patented July 3, 1906.

Application filed March 26, 1906. Serial No. 308,180. Term of patent 14 years.

To all whom it may concern:

Be it known that I, CHARLES H. PFEIL, a citizen of the United States, and a resident of Chicago, in the county of Cook and State of Illinois, have invented a new, original, and ornamental Design for Rings, of which the following is a specification, reference being had to the accompanying drawings, forming a part thereof.

Figure 1 of the drawings is a perspective

view of a ring, showing my new design. Fig. 2 is an elevation of the ring viewed from the left of Fig. 1. Fig. 3 is a top plan of the same.

I claim—

The ornamental design for a ring as shown.
CHARLES H. PFEIL.
